ATTORNEY

UNITED STATES PATENT OFFICE

ARTHUR LUFT, OF LYNBROOK, NEW YORK

GARMENT

Application filed January 9, 1930. Serial No. 419,485.

This invention relates to clothing, especially to clothing of the type having a leg portion which is provided with an opening in one side for convenience in inserting the foot of a wearer and more particularly to a unitary garment of the type which is fabricated from more than one kind of material.

A principal object of the invention is to provide a unitary garment of the type specified which may be made from practically water proof material for that portion of the garment which extends from the foot of the wearer to or just above the knee and of a different material, preferably one of good heat insulating properties, at least better heat insulating properties than the lower portions of the garment, for that portion of the garment extending from the water proof material up to the waist of the wearer.

20 A further object of the invention is the provision of a garment of the type specified which is made of material adaptable for combination with fastening means of both the slide and snap type.

25 Other objects and advantages will appear as the description of the particular physical embodiment selected to illustrate the invention progresses and the novel feature of the invention will be particularly pointed out in the appended claim.

30 In describing the invention in detail and the particular physical embodiment selected to illustrate the invention reference is had to the accompanying drawing wherein like characters of reference designate corresponding parts throughout the several views, and in which:

35 Figure 1 illustrates a child's legging embodying the invention; Fig. 2 is a side view of the garment as shown by Fig. 1; Fig. 3 is an enlarged view illustrating the bottom of the leg opening fastening means used with applicant's invention together with an in-

40 step strap fastening means, all in open position; Fig. 4 shows the same parts as are illustrated by Fig. 3 but with the parts in closed position.

45 In the drawing, 1 designates generally what is commonly known and called a child's

legging. This legging includes leg portions 2 and 3 and a body portion 4.

In accordance with applicant's invention, the leg portions 2 and 3 up to about the point 5, that is, up to or perhaps just above the knee of a wearer are formed of water proof material, such as any of the well known fabrics now being used as water proof fabrics or leather. By so making the lower portion of the garment of such fabric the limbs of the wearer are protected in those places most likely to come in contact with water, falling or splashing thereon.

The portion 4 of the garment, that is, from the point 5 at or just above the knee to the waist of the wearer is formed of a material, as cotton or wool, of much better heat insulating properties than the material of which the lower portion of the leg is formed so that the upper portion of the legs and the lower portions of the body of the wearer can be kept much more warm and comfortable than would be the case if the entire garment were of water proof material which generally does not have the heat insulating properties of a garment which should be used to conserve the heat of the wearer, at any rate, the ordinary water proof material, because, probably, its heat conductivity is greater, feels cold to the touch but the material contemplated by applicant for the portion of the garment between the point 5 and the waist will have better insulating properties than the lower portion of the garment and will in addition be substantially less heat conducting and so not feel cold to the touch of a wearer.

The connection between the upper portion 4 and the lower portion 2 may be made in any of the ordinary and well known ways such as by sewing, as by forming any of the ordinary and well known seams and in addition a tape as 6 may be applied over the seam to strengthen and give a finish.

Applicant prefers to insert an elastic as 7 in the back part of the portion surrounding the waist of a wearer so that the garment will be held resiliently in place.

In order to render the garment easy to put on, the upper portion 4 is bifurcated along the line 8 and the two parts are supplied with

the appropriate parts of any ordinary and well known slide fasteners as 9 operated by the pull 10. In order to insure that the slide fastener 9 will not open a snap fastener 11 is added which firmly holds the upper parts of the two portions of the bifurcated garment together.

10 The leg portions 2 and 3 of the garment are each bifurcated and provided with slide fasteners, as 12, so that no difficulty will be experienced in inserting and withdrawing the foot of the wearer. After the garment is in place the pull 13 of the slide fastener is drawn to the lowest point as shown in Fig. 4. The parts are thereby drawn tightly together to 15 form a substantially water-tight joint throughout the lower waterproof leg portion. In order to be certain that the pull 13 will remain at the lower point of the garment and the separate portions will not pull apart, applicant has provided the tab 14, fastened to 20 one portion as at 15 and engageable with the snap fastener 16 on the other portion. When the pull 13 is drawn to its lowest point, as shown in Fig. 4, and the tab 14 fastened by 25 means of the snap fastener 16 the pull is practically out of sight and there is no danger of its catching in nearby objects and no danger of it being accidentally moved upwardly so as to separate the portions of the leg.

30 In order to insure that the garment will remain snugly in engagement with the shoe of the wearer, the instep strap 17 is provided, fastened at one edge 19 of the opening for 35 the foot and provided at the other end with one part 20 of a separable snap fastener. The other portion 21 of the separable snap fastener is attached to the tab 14. When the garment is in place the instep strap 17 is 40 moved into position under the instep and the portion 20 snapped into engagement with the portion 21 so that the garment is then held securely in position. By securing the instep strap in this manner, the tab permits a slight 45 yielding movement which facilitates the fastening of the parts and also accommodates itself to the changing positions of the foot and prevents undue strains on the strap.

50 Although I have illustrated slide fastenings as at 9 and 12 it is to be understood that the commonly used fastenings such as buttons and laces may be equally well used and that I do not desire to be understood as specifying any particular type of slide 55 fastener.

55 As a suitable material for the upper portion 4 of the garment wool has the preference although cotton, silk or rayon may well be used or combinations thereof with wool.

60 Although I have particularly described but one physical embodiment of my invention and explained the principle and construction thereof, nevertheless, I desire to have it understood that the form selected is merely 65 illustrative but does not exhaust the possible

physical embodiments of the idea of means underlying my invention.

What I claim as new and desire to secure by Letters Patent of the United States, is:

70 A child's unitary garment adapted to afford protection against cold and dampness comprising in combination lower leg portions formed of a tough water-proof material, each leg portion being provided with a slot on the outer side from the bottom upwardly 75 through a portion of its length and having fastening means to close the slot, and an upper leg and body portion formed of a woven fabric having better heat insulating properties than the lower portion, said upper 80 portion being provided with a slot closed by a fastening means and extending from the top of the garment along one side into the upper leg portion.
